UNITED STATES PATENT OFFICE.

DOMENICO CALARCO, OF BURLINGTON, VERMONT.

SOUNDING TOY.

1,413,454.

Specification of Letters Patent. Patented Apr. 18, 1922.

Application filed June 18, 1921. Serial No. 478,596.

To all whom it may concern:

Be it known that I, DOMENICO CALARCO, a subject of the King of Italy, residing at Burlington, in the county of Chittenden and 5 State of Vermont, have invented certain new and useful Improvements in Sounding Toys, of which the following is a specification.

This invention relates to toys and has special reference to that class of toy known 10 as sounding toys. More particularly the invention relates to a buzzer.

Toys somewhat similar to the present invention have been previously made but such toys have not been of attractive appearance.

15 One important object of the present invention is the production of a toy of this description which will have an attractive appearance and which will thus induce children and others to purchase the same.

20 In toys as previously constructed use has been made of a diaphragm to which a string is connected, the string being looped around the stick and being rosined at the point of contact with the stick.

25 A second important object of the invention is to provide an improved toy of this class wherein the use of rosin will be unnecessary.

A third important object of the invention is to provide a toy of this class with 30 improved means for holding the diaphragm in position.

With the above and other objects in view, the invention consists in general of certain novel details of construction and combinations of parts hereinafter fully described, illustrated in the accompanying drawings, and 35 specifically claimed.

In the accompanying drawings, like characters of reference indicate like parts in the 40 several views, and :-

Figure 1 is a perspective view showing the manner of using the toy, the form illustrated in this view being that of an aeroplane.

45 Figure 2 is a side elevation partly in section of the apparatus shown in Figure 1.

Figure 3 is a perspective view of a second form of the toy, the form in this instance being that of a dragon-fly.

50 Figure 4 is a cross section through such a toy showing a second method of securing the diaphragm in position.

One of the important features of all of the forms of which this toy is made is the form 55 of body which is known as fusiform or stream-line and upon such a body as this

can be built any number of attractive designs such as aeroplane and dragon-fly herein shown as well as many others such as birds, fish and a variety of objects not 60 deemed necessary to be specifically illustrated or described since the body on which they are constructed is common to all and the invention is not limited to any specific ornamental features.

65 In each of the forms used there is provided at about the center of gravity of the body a vertical well or opening 11, the body itself being illustrated at 10. In the form shown in Figures 1 and 2 the upper part of 70 this well 11 is a counter-sunk portion as at 12 and across the lower portion in this counter-sink is stretched a diaphragm 13 which may be of any preferred material such as paper, parchment or the like but I have 75 especially found that parchmentized rabbit skin is highly efficient for the purpose. This thin diaphragm 13 is held in position by means of a suitable ring 14 covered by the wing member 15 of the aeroplane the latter 80 having an opening 16 through which the diaphragm 13 is exposed.

In the form shown in Figures 3 and 4 the counter-sink is dispensed with and a diaphragm 17 extends over the opening 11 and 85 is secured to the sides of the body by any suitable means. This form also is covered with a wing member 18 having an opening 19 therein through which said diaphragm is exposed.

90 As a result of my experiments in this line I have found that the most suitable material for the suspending means is horse-hair because with horse-hair it is not necessary to use any rosin to produce the desired result 95 while with any form of string or twine rosin is essential. To secure the suspending means to the device I provide a pair of spaced opening 20 in the diaphragm and through these openings there is passed the horse-hair 100 21. At 22 is the manipulating wand or stick having a notch 23 near its points so that the horse-hair 21 may be looped around the stick in the notch as clearly shown in Figures 1 and 2.

105 Attached to the fusiform body in Figures 1 and 2 is a propeller 24 and tail 25 while in Figure 3 the body is provided with a head 26, legs 27, and tail 28, these parts being in addition to the wing parts previously described. Thus the article has the similitude of some natural object.

In using the invention it is merely necessary to moisten the horse-hair, as with saliva at its point of engagement with the wand 22 and then swing the toy around the wand.

- 5 This will cause a loud humming noise due to the vibration of the diaphragm.

There has thus been provided a simple and efficient device of the kind described and for the purpose specified.

- 10 It is obvious that minor changes may be made in the form and construction of the invention without departing from the material principles thereof. It is not therefore desired to confine the invention to the exact 15 form herein shown and described, but it is wished to include all such as properly come within the scope claimed.

Having thus described the invention, what is claimed as new, is:—

- 20 1. In a toy of the class described, a fusi-

form body having an opening extending therethrough, a vibratory diaphragm stretched across said opening, balancing wings extending transversely across the top of the body and having an opening through 25 which the diaphragm is exposed, a tail on the smaller end of the body, and suspension and operating means connected to said dia- phragm.

2. In a toy of the class described, a fusi- 30 form body having an opening extending vertically therethrough and countersunk at its upper end, a vibratory diaphragm stretched across the lower part of the opening within the counter-sink, a retaining ring engaging 35 the upper surface of the diaphragm peripherally, and suspension and operating means connected to said diaphragm.

In testimony whereof I affix my signature.
DOMENICO CALARCO.
